SPECIMEN HOLDER FOR POLISHING MACHINE
Donald G. Zimmerman, Park Ridge, Ill., assignor to Precision Scientific Company, Chicago, Ill., a corporation of IllinoisFiled Aug. 9, 1963, Ser. No. 301,082
1 Claim. (Cl. 51—217)

The present invention relates to specimen holders and more particularly to a holder for mounting embedded metallurgical samples in an automatic polishing machine.

An automatic polishing machine for metallurgical samples is usually designed to accommodate three or more samples embedded in circular mounts or carriers molded of plastic, which may be 1" or 1 1/4" in diameter and from 1/2" to 3/4" thick. One design of specimen holder is in the form of a disc having windows or openings to receive the mounts and laterally grooved for receiving a clamping band which clamps all of the mounts simultaneously in position. In another common type of specimen holder a slot is cut through the material surrounding each of the openings and individual clamping screws are provided for pulling the material on the two sides of the hole together to secure the clamping action. Such devices are inherently limited in usefulness by reason of the fact that they can accommodate only one diameter of mount. Moreover, the various closely fitted surfaces provide cracks and crevices for lodgement of the grit so that it is difficult to flush the carrier free of one grade of grit before proceeding to a finer grade in the successive polishing steps.

It is an object of the present invention to provide a new and improved specimen holder which is capable of accommodating mounts within a range of diameter so that one holder may suffice in place of the several normally required. It is another object to provide a specimen holder in which each of the mounts is securely clamped in position with only a single set screw but which nevertheless insures automatic alinement of the mounts with respect to the holder body with no possibility of dislodgement or cocking. It is moreover an object of the present invention to provide a specimen holder for an automatic polishing machine or the like which is of open construction, free of any closely spaced, closely fitted, or "parallel" surfaces and which therefore makes it an easy matter to flush the holder and the mounts secured therein completely free of grit as required in the successive polishing steps. Finally it is an object of the present invention to provide a specimen holder which, in spite of the advantages which it offers, is nevertheless of simple and inherently inexpensive construction.

Other objects and advantages of the invention will become apparent upon reading the attached detailed description and upon reference to the drawing in which:

FIGURE 1 is a plan view of a specimen holder constructed in accordance with the present invention and showing specimen mounts clamped in place.

FIG. 2 is a section looking along the line 2—2 in FIG. 1.

While the invention has been described in connection with a preferred embodiment, it will be understood that I do not intend to limit the invention to the exact form shown but intend to cover such modifications and alternative constructions as may be included within the spirit and scope of the appended claim.

Turning now to the drawing there is shown a specimen holder 10 of disc shape having a flat front surface or face 11 and a back surface 12 parallel thereto with a circular periphery 13. In use the specimen holder is driven in a polishing machine (not shown) by means of a friction drive consisting of two idler wheels and one drive wheel, rotating in contact with the periphery of the holder.

2

Mounting post 15, which may be press fitted in the holder body, is used to mount weights which determine the polishing pressure. Formed in the holder body are a plurality of openings or windows, in the present instance three in number as indicated at 16, 17, 18, and which are symmetrically distributed about the axis.

In accordance with the present invention each of the windows extends to within a short distance of the periphery and provides a peripheral wall penetrated by a single set screw, with each of the windows having intersecting walls symmetrically arranged with respect to the clamping axis of the set screw so that line contact is established with a circular mount at widely spaced, symmetrically located points when the set screw is tightened. Thus in the case of the present device, and taking the window 16 as representative, it will be noted that it extends to within a relatively short distance of the periphery 13 to define a peripheral wall section 20. This wall has formed therein a tapped hole 21 into which is screwed a set screw 22 defining a clamping axis 23. Symmetrically arranged with respect to the clamping axis are a pair of intersectingly arranged walls 24, 25 which serve as clamping surfaces. Since the holder and mounts preferably have appreciable thickness as indicated at FIG. 2, parallel lines of contact are established having appreciable length to insure axial alinement. Preferably the clamping surfaces 24, 25 are straight or of only limited curvature bearing an average angle with respect to the clamping axis on the order of 45°.

Consequently, when a disc shaped mount is inserted into the window and the set screw 22 turned tight, the mount is limited to line, or near line contact at the points of engagement indicated at 31, 32 respectively. Such line contact acts to distribute the clamping pressure over the entire axial length of the mount while avoiding closely spaced or "parallel" surfaces which might serve to entrap grit. Thus the openings 33, 34 which are defined on the opposite side of the mount while of generally crescent shape are sufficiently "open" and sufficiently blunt at the ends so that a pressure stream of water may be directed through the assembled holder with assurance that all of the grit will be flushed away at the end of each grinding step and when the grit size is changed to a finer grade.

The present holder construction while minimizing the area in contact with the mount nevertheless serves to hold the mount securely perpendicular to the face of the holder while preventing any tendency toward cocking of the mount during the polishing operation even though relatively light clamping pressures are applied at the set screw. In short, since the clamping surfaces 24, 25 are perpendicular to the face of the holder, the widely spaced lines of contact 31, 32 with the mount are precisely parallel with one another which insures that the mount will be clamped with its axis precisely parallel to the axis of the holder without any care or attention on the part of the operator.

It is one of the features of the present construction that it is capable of accommodating cylindrical mounts having a wide range of diameter. In the particular embodiment shown, the mount 35 in window 17 is of standard 1" diameter whereas the mount 36 in window 18 has a diameter of 1 1/4". It will be apparent that the holder may be modified to accommodate an even wider range of mount diameter simply by scaling it up in size.

Since the mount is of one piece construction, for example of cast aluminum, it is inexpensive to manufacture and capable of constant use over a long period of time without wear or loss of accuracy.

I claim as my invention:

A specimen holder for a metallurgical specimen polishing machine or the like for holding cylindrical specimen mounts which comprises a one piece body of disc shape having a flat face and having a plurality of windows

formed therein symmetrically distributed about the axis and extending to within a short distance of the periphery to define individual peripheral wall portions, a set screw penetrating each of the peripheral wall portions and oriented along a clamping axis, each of said openings having intersectingly arranged clamping surfaces at a relatively wide angle parallel to the holder axis and symmetrically arranged with respect to the clamping axis, the disc having appreciable thickness so that, when a cylindrical mount is inserted into one of the windows and the set screw turned tight, line contact is established at two widely spaced points on the periphery of the mount symmetrically arranged with respect to the point of contact of the set screw, said intersectingly arranged surfaces being substantially straight and connected at each of their op-

posite ends by accurate surfaces on opposite sides of the mount so as to define a pair of generally crescent-shaped openings on the opposite sides of the mount which are relatively wide and blunt ended to facilitate flushing of the holder and assembled mounts free of one size of grit prior to use of grit of progressively finer grade.
